UNITED STATES PATENT OFFICE

152,249

DESIGN FOR A SERVICE CART FOR SERVICE
STATIONS AND THE LIKE

Alexander P. Fox, University City, Mo., assignor
to Lincoln Engineering Company, St. Louis,
Mo., a corporation of Missouri

Application December 20, 1947, Serial No. 143,264

Term of patent 3½ years

(Cl. D14—3)

To all whom it may concern:

Be it known that I, Alexander P. Fox, a citizen of the United States and a resident of University City, St. Louis County, Missouri, have invented a new, original, and ornamental Design for Service Cart For Service Stations and the like, of which the following is a specification, reference being had to the accompanying drawing, forming part thereof in which

Fig. 1 is a perspective view of a cart for service stations and the like, showing my new design on an enlarged scale in comparison with the other disclosures.

Fig. 2 is a front elevation viewed from the right of Fig. 1;

Fig. 3 is a rear elevation viewed from the left of Fig. 1;

Fig. 4 is a top plan view; and,

Fig. 5 is a side elevation viewed from the far side of Fig. 1.

I claim:

The ornamental design for a service cart for service stations and the like, substantially as shown.

ALEXANDER P. FOX.
